UNITED STATES PATENT OFFICE.

MAURICE M. KASANOF, OF NEW YORK, N. Y.

DRIER FOR TUBULAR FABRICS.

Application filed December 2, 1926. Serial No. 152,226.

My invention relates to a drier for fabrics and more particularly to a drier for tubular fabrics, such, for example, as jerseys, silk, cotton and other tubular fabrics.

5 The general object of my invention is to provide a drier for the indicated purpose improved with respect to the means for so disposing the fabric in the drier as to make for the effective drying of the fabric.

10 A further object is to provide a drier assemblage including means to direct heated air under pressure to the drier body.

Reference is to be had to the accompanying drawings forming a part of this specification, it being understood that the drawings are merely illustrative of one example of the invention.

Figure 1 is a side elevation of a drier for tubular fabrics embodying my invention.

20 Figure 2 is a transverse vertical section of the upper portion of the drier, the section being indicated by the line 2—2 of Figure 1.

Figure 3 is an elevation of the drier with 25 means to supply drying air under pressure and other features to be hereinafter referred to.

In carrying out my invention in accordance with the illustrated example, a hollow 30 body 10 is provided over which a fabric A may be drawn, said body being cylindrical, oval or other suitable shape. I have illustrated a fabric spreader 11 above the body secured to the latter by base members 12 on 35 said spreader, the base being secured to a top member 13 on the body 10. The spreader 11 is not claimed herein but forms part of the subject matter of an application for patent pending concurrently herewith.

40 In order to dispose an annular zone of the fabric A in such manner that the drying air will be effectively applied, I form on the body 10 annular flanges 14 spaced from each other. In the zone of the body 10 between 45 the flanges 14, air outlets 15 are formed, these advantageously consisting of an annular series of jet orifices 15. Thus when the fabric A is drawn over the body 10 the said fabric will be spaced from the outer

surface of said body and form an annular 50 chamber into which the air escaping from the openings 15 will be discharged so that the air will pass outwardly through the fabric and carry off the moisture therein.

The numeral 16 indicates an air inlet in 55 the bottom of body 10, said inlet being formed in a nipple 17. Said body 10 is shown as mounted on the upper end of a standard 18, the upper end of which has threaded engagement with nipple 17. The 60 numeral 19 indicates a suitable base from which the standard 18 rises. To maintain a supply of drying air in the body 10 I connect therewith an air supply pipe 20 having a valve 21, said pipe being connected 65 with an air tank 22 which is supplied with air by a pipe 23 from an air pump 24 here conventionally indicated. Any suitable heating means may be employed if desired in connection with tank 22 for heating the 70 latter when it is desired to direct heated air against the fabric, but cold air under pressure is generally effective.

In some cases it is desirable to supply a bleaching agent or the like within the fabric, for which purpose I have conventionally shown a container 25 which connects by a pipe 26 with a stand-pipe 18 and is provided with a valve 27.

With the described construction, the body 80 10 is in practice disconnected from the standard 18 and the fabric is drawn downwardly over said standard and gathered thereon. The body 10 with the spreader 11 thereon is restored to the standard 18 and 85 made fast. The fabric is then drawn upwardly over the body 10 and spreader 11. The drying air is supplied through the inlet nipple 16 of the body 10, escaping at the openings 15. The fabric when drawn 90 upwardly passes against the flanges 14 and is subjected to the action of the drying air discharged from the openings 15. As the fabric continues its movement over the upper portion of the body 10 and over 95 spreader 11 the drying action is completed, the major portion of the moisture being driven off between the flanges 14.

I would state furthermore that while the illustrated example constitutes a practical embodiment of my invention, I do not limit myself strictly to the exact details herein, since, manifestly, the same can be considerably varied without departure from the spirit of the invention, as defined in the appended claim.

What I claim is:

A drier for tubular fabrics including a hollow body over which a fabric to be dried may be drawn, and external flanges on said body spaced from each other, said body between said flanges having air outlets through which air will escape.

MAURICE M. KASANOF.
